UNITED STATES PATENT OFFICE.

JOSEPH F. MARTTER, OF COLUMBUS, OHIO.

LOUVER-SIGN.

1,150,444.

Specification of Letters Patent. Patented Aug. 17, 1915.

Application filed March 12, 1914. Serial No. 824,177.

To all whom it may concern:

Be it known that I, JOSEPH F. MARTTER, a citizen of the United States, residing at Columbus, in the county of Franklin and 5 State of Ohio, have invented certain new and useful Improvements in Louver-Signs, of which the following is a specification.

My invention relates to louver signs of a type to be conveniently used for ventilating 10 the basement of store rooms etc., and adapted to be placed directly beneath the usual form of plate glass front. My device is particularly adapted for use as an advertising medium in this connection, the advertising 15 being printed or otherwise placed upon its face.

One object of my invention is the provision of a sign of this type, which may be readily removed at any time from its position and a different sign used to replace it if desired.

In its preferred form, I provide a series 20 of horizontally disposed louvers integrally formed therewith. The provision of these 25 louvers has a peculiar attracting property, which may be used to advantage by placing the proper advertising literature thereon.

My invention also resides in the provision 30 of a peculiar type of nailing strip, which may be permanently applied to the store front or to the front of the building in any desired manner. This nailing strip and the sign proper are formed to coöperate with each other to hold the sign body securely in 35 its position.

The preferred embodiment of my invention is shown in the accompanying drawings, in which similar characters of reference designate corresponding parts, and in 40 which:

Figure 1 is a face view of my sign assembled, Fig. 2 is a face view of the nailing strip shown detached, Fig. 3 is an enlarged section taken on line 3—3 of Fig. 1 and 45 looking in the direction of the arrows, and, Fig. 4 is an enlarged section taken on line 4—4 of Fig. 2 and looking in the direction of the arrows.

In the drawings, my device is shown as 50 comprising a metal body, the center and major portion 1 of which is provided at regular intervals with horizontally disposed louvers 2. The two side edge portions 3 and the upper and lower edge portions 4 55 and 5 respectively, are bent back slightly,

both for the purposes of attractiveness and also to insure the proper spacing of the sign from the building when it is applied, so that the free edges of the louvers 2 will not lie in contact with any portion thereof. 60

My sign is particularly adaptable to serve the purpose of a ventilator and this is one of the reasons why I have provided these louvers, although in placing the signs among a large number of merchants, various structures are encountered and, therefore, it is good policy to provide the portions 3, 4 and 5 to prevent engagement of the louvers with the building. 65

Along the upper edge of the body of the sign, I have also provided a flange 6, which flange may be of a width to permit the merchant to apply his own name or some other preferred type of lettering. This flange is shown as being provided with three tongues 7, cut out of the body of the metal itself and bent to hook form, as is more clearly shown in Fig. 3. It is desirable to locate these tongues in the manner shown in Fig. 1, in which the two adjacent the side edges are placed near the top edge of the flange, while that one shown in the middle is adjacent the lower edge. The purpose of this will be 70 hereinafter explained. 75

In order that my sign may be conveniently applied, I have provided a nailing strip 8, which nailing strip is practically of U-shape, although its inside edges are doubled back, as is shown at 9 and the strip, as a whole, applied by means of nails or screws 80 85 90 95 100 105 110

10 piercing the outer face of the strip, as well as these turned back portions 9. It is only necessary to provide one of these strips and in order that it coöperate with the tongues 7, I have provided a plurality of slotted openings, these slotted openings being of peculiar form in that the portions 11 are large enough to admit the entering of the tongues 7, while the portions 12 are somewhat larger to permit the sign as a whole, to drop downwardly a slight distance. After this, there is provided a narrow slotted portion 13 of a width approximately equaling the thickness of the metal itself. As stated, the portions 11 are of a height to permit the passage of the bent tongues 7 and after the sign has been placed in this position, it is moved slightly to the left, whereby the tongues 7 enter the enlarged portions 12 and the sign, as a whole, is per-

mitted to drop slightly. The shoulders 14 formed by these two slotted portions prevent the sign from being accidentally moved to the right or, in other words, it is impossible to move them to the right unless they are slightly elevated. After this operation, the sign is again moved to the left and the tongues 7 caused to enter the slots 13.

In order to more securely lock the signs in their positions, I have provided the face of the nailing strip 8 with a lip 15, which lip is preferably disposed on the left hand end and doubled back to lie parallel with the face of the strip. The length of this lip is such that it will partially cover one edge of the sign after the sign has been bodily moved the first time to engage the larger slotted portions 12. It will, therefore, be apparent that removal of the sign is prevented because of this lip and it is, therefore, necessary to move the same so that the tongues 7 will lie in the portions 11. However, accidental movement to this position, is prevented because of the shoulders 14. Also, because of the staggered relation of the lips 7, more stability will be given the sign and oscillating movement due to wind etc., will be prevented.

In order that the sign may lie in a secure manner, I have provided its lower edge with a flange 16, this flange being bent to U-shape as is shown at 17. The thickness of the U-portion of this flange, is such that it equals the thickness of the nailing strip itself plus the thickness of the upper flange 6 and, therefore, the face of the sign will at all times lie in a plane parallel with the face of the building to which it is attached.

From the above description, it must be apparent that I have provided a comparatively simple type of sign and one which may be conveniently used for advertising purposes as well as for ventilation and light to the basement of a building. If a merchant desires to have a number of these

signs in stock, they may be removed and replaced with ease.

What I claim, is:

1. A sign comprising a body portion having a display face formed thereon, a nailing strip adapted to be permanently attached to a building, said strip having slots therein, an upwardly extending flange portion on the upper edge of said body, said flange portion being arranged to overlie the front face of said strip, tongues carried by said flange to engage said slots, and a rearwardly extended flange portion on the lower edge of said body, said last-named flange being of a depth equaling the thickness of said strip plus the thickness of said first-named flange and arranged to have its rearmost portion rest against said building when the sign is mounted thereon.

2. A sign comprising a body portion having a display face formed thereon, a U-shaped nailing strip adapted to be permanently attached to a building, said strip being provided with slotted openings large at one end and small at the other end, a lip carried by one end of said strip doubled back to extend over the face of said strip, the smaller ends of said slots extending toward said lip, an upwardly extending flange portion on the upper edge of said body, said flange portion being arranged to overlie the front face of said strip, and tongues carried by said flange to engage said slots, said tongues being insertible in the large ends of said slots, said body being then adapted to be slid into position to engage said flange between said strip and its lip and said tongues in the smaller ends of said slots after said tongues are in said slots.

In testimony whereof I affix my signature in presence of two witnesses.

JOSEPH F. MARTTER.
